(57) **CLAIM**

The ornamental design for a medical X-ray imaging apparatus, as shown and described.

DESCRIPTION

FIG. 1 is a front view of a medical X-ray imaging apparatus; FIG. 2 is a rear view of the medical X-ray imaging apparatus; FIG. 3 is a left side view of the medical X-ray imaging apparatus;

FIG. 4 is a right side view of the medical X-ray imaging apparatus;

FIG. 5 is a top view of the medical X-ray imaging apparatus; FIG. 6 is a bottom view of the medical X-ray imaging apparatus;

FIG. 7 is a perspective front view of the medical X-ray imaging apparatus; and,

FIG. 8 is a perspective rear view of the medical X-ray imaging apparatus.

1 Claim, 8 Drawing Sheets
